WILLIAM L. LAING, OF MONTREAL, QUEBEC, CANADA

CAR DUMPING DEVICE

Application filed January 22, 1929, Serial No. 334,272, and in Canada November 10, 1928.

This invention relates to new and useful improvements in car unloading devices and particularly to such devices in which the car is suitably supported and rotated into a position at which the contents of the car are unloaded or dumped.

The objects of the invention are to provide a machine which when set to receive or deliver a car will do so without undue shock on the hoisting or rotating gear, forming part of the machines; to provide improved means for placing the car in position; to provide means for clamping the car to the rotating frame before operating same and means for regulating the machine so that it will automatically operate through a predetermined sequence of operations.

According to my invention, I provide a car receiving platform which is removably supported on a suitable foundation, said platform and foundation being provided with means to accurately centre and locate the track carried by the platform with the approach and lead off tracks. The platform is suspended from a hoisting unit carried by a circular frame which is mounted on rollers and operated by suitable rotating mechanism. The centre of the frame is provided with an opening adapted to receive the car and means are provided for equalizing the clamping of the car against one side of the said opening. Means are also provided for regulating the machine so that it will first clamp the car in position, then rotate the frame from normal to dumping position and vice-versa and finally lower the dumped car, so that it may be quickly discharged from the machine.

In the accompanying drawings which show one form of my invention.

Figure 1 is an end view of my improved car dumping mechanism.

Figure 2 is a side elevation of the mechanism shown in Figure 1.

Figure 3 is an end elevation of the machine with the car in its raised or dumping position.

Figures 4 and 5 are respectively detail views of the automatic cut out devices for the

hoisting and rocking movement of the lifting platform.

Figure 6 is a sectional side elevation of the equalizing beam with safety device operated thereby.

Figures 7 and 8 are side and end views respectively of the platform centering devices.

Referring more particularly to the drawings, 11 designates the foundation of the machine which is adapted to support the ends 12 and 13 of the approach and discharge tracks. Supports 14 are provided in proximity to said ends and are preferably made in the form of an inverted V. These supports are adapted to engage with centering brackets 15 secured to the underside of a car receiving platform 16. The brackets 15 have inverted V shaped recesses which in conjunction with the centering supports 14 are adapted to align the rails 16a carried by the platform with the rail ends 12 and 13. The platform consists of longitudinal girders 17 adapted to support the rails 16a and these girders are suitably braced together by the members 18. Secured to the underside of the girders or members 18 and in proximity to each end thereof are the lifting beams 18a. These beams extend transversely of the track and extend beyond the girders. Rotatably mounted in the ends of the beams are the hoisting rope return pulleys 19. The shock due to the movement of the car 20 shown in dotted lines in Figure 2 when being placed into position on or being removed from the platform is taken up directly by the foundation through the supports. The platform is positioned so that it projects outwardly beyond the ends of a tubular housing including circular end frames 20b which rest on rollers 21 rotatably mounted in suitable bearings carried by the foundation 11. The platform in its normal or car receiving and discharging position is clear of the opening 22 in the member 23.

Mounted in suitable framing members 23 secured to the circular member are the pulleys or sheaves 24. The hoisting ropes 25 are reeved around the sheaves or pulleys 24 and 19 and are anchored at one end to the

framing member 23 as indicated at 25a. The other ends of the ropes are secured to hoisting drums 25 rotatably secured to the members 23 and driven through suitable gearing 24a from the motors 25c. The arrangement of pulleys is such that when the cables or ropes are wound upon the drums, the platform is lifted from its supports together with the car to bring the upper edge of same tightly against the equalizing beam holding member 26 and bring the sides of the car against bearing members 22a on the side 27 of the opening 22 and away from the hoisting machinery side of the frame.

5 To prevent sudden side movement of the platform when being hoisted, rollers 28 are secured to the sides thereof and these rollers engage with the inclined guide members 29 secured to the side 27. The rollers and guides 20 are so positioned that the platform will gradually approach the side 27 until the car bears against said side then the hoisting movement of the platform is in the vertical direction. The rollers 28 and guides 29 also act 25 as a positioning means for the platform when the empty car is being lowered. The equalizing holding or bearing members are preferably suspended from the rotating frame so as to permit of a slight vertical movement. As 30 the car is raised its upper edges contact with the equalizing members and raises same until they come in firm contact with the frame. The vertical movement of the equalizing members actuate the lever 30 which operate 35 the switch 31 which cuts off the current to the hoisting motors 25a and directs said current to the motor 32 which is adapted to operate the rotating mechanism. The motor 32 rotates the drums 33 through suitable gearing 40 34. The drums are grooved to receive ropes 35 the ends 36 and 37 of which are secured by adjusting shackles 38 to anchor brackets 39 secured to the periphery of the rotary frame. These brackets are spaced apart on 45 the periphery so that the rotating frame may be moved through an angle of approximately 180 degrees or to the desired position. A limit switch 40 is provided for controlling the degree of rotating movement of the frame.

50 Secured to the periphery of the frame is an inclined projection 41 which is adapted to contact with a roller 42 secured to the end of the limit switch arm 43.

55 Automatic cut out switch mechanism may also be provided to cut off the current to the hoisting motors to permit correction to the platform level to be made in the event that one end of the platform is raised or lowered in advance of the other end. One arrangement suitable for this purpose is shown to 60 advantage in Figs. 2, 4 and 5. As shown to advantage by these figures, a vertical post 45 is attached to the car hoisting platform by means of a bracket 46. Near its upper end, 65 post 45 is provided with a vertical slot 46a

to receive one end of a horizontally disposed lever 47. Lever 47 is pivotally movable in a suitable bearing carried by a motor 27a located at the side of the opening 22 remote from the aforementioned frame 27. The opposite end of lever 47 is provided with an inverted U-shaped portion 48 embracing a roller 49 suitably connected to the movable element of a cut out or limit switch 31a, the arrangement being such that any side motion of lever 47 causes one side of the fork portion 48 to depress the roller 49 and thereby operate the switch 31a. The lower end of the slot 46a communicates with an angularly disposed slot 50. During the platform lifting operation the lever 47 remains in the vertical slot 46a until the car has been raised to the desired point and is firmly clamped in elevated position. Any tendency to lift the platform beyond this limit causes the lever 47 to enter the angular slot 50 and to actuate the switch 31a. In the event that one end of the platform is raised above the other, the upper end of the post 45 will swing in the direction of the lower end of the platform and in so doing will actuate the switch 31a.

In the present instance, each equalizing member 26 is shown suspended from the upper portion of one of the frame members 20b. The suspension means is shown to advantage in Fig. 6 and includes an inverted T member 26a suspended from the frame member 20b. The head of the T member 26a is loosely received between a plate 26b and a pair of angle arms 26c carried by the equalizing beam 26. The suspension connection thus provided between the frame member 20b and the equalizing member 26 is such as to permit the latter to have the limited vertical movement necessary to operation of the lever 30 and switch 31. In the present instance, the suggested arrangement of the equalizing beams, gears, frames, and limit switches is largely diametrical, as it is obvious that the specific designs and mounting of these elements is susceptible to various modifications within the knowledge of those skilled in the art.

The operation of the car dumping or unloading machine is as follows. The platform is in its normal position, that is, resting solidly on the supports secured to the foundation with the platform rails in alignment with the approach and lead off rails. In this position, the hoisting ropes are slackened off and there is no strain on the hoisting ropes. The platform is clear of the rotating frame. The car to be dumped is then moved into position on the platform. The hoisting motors are then set in operation and lift the platform and car and in so doing the car is brought into frictional contact with bearing members in the frame. If one end of the platform should be lifted in advance of the other, the limit switch 31a in circuit with the

motor is brought into operation to locate the circuit to the hoist motor and this correction may be automatically arranged by providing two limit switches 31a, one for each side and having the switches spring operated so that the switch on one, the high side, will cut out the motor controlling this side until the other motor has brought the platform level. The car is then hoisted until it is brought into contact with the equalizing beam members. The beams move upwardly and the car is clamped thereagainst. The upward movement of the beams operate the hoisting limit switches 31 to cut out the current from the hoisting motors and direct the current towards the rotating motor. This motor is then brought into play and moves the circular frame through an angle of approximately 180 degrees so that the material within the car is dumped. This rotative movement is controlled by the limit switch 40. On completion of the dumping the direction of rotation of the motor is reversed and the frame rotated back to its normal position. The car is then lowered and in lowering moves clear of the frame and is brought automatically into alignment with the approach and lead off tracks through the medium of the V-shaped members. The car is then moved from the platform.

The device is simple in operation and the mechanism is protected against any movement which would be detrimental to the working of the machine.

35 I claim:

1. In a car unloading device, a rotating frame, rollers for supporting the frame, a car receiving platform adapted to pass through and extend beyond each side of the frame, 40 said platform being clear of the frame in its car receiving position and resting on suitable bearings, means to raise the platform with car thereon to first move it towards the side of the frame and then clamp the top of the 45 car against the top of the frame, and means to control the level of the platform during the hoisting operation.
2. In a car unloading device, a rotating frame, rollers for supporting the frame, a 50 car receiving platform, carrying tracks for the car passing through the frame, means for supporting the car independent of the frame, means for lifting the platform with car thereon to clamp the car against one side 55 and the top of the frame, means for limiting the hoisting movement of the loaded platform, and means to automatically control the level of the platform during the hoisting operation.
3. In a car unloading device, a rotating frame, rollers for rotatably supporting the frame, a car receiving platform passing through and extending on both sides of the frame, means secured to the frame for lift- 65 ing the platform with car mounted thereon

to clamp the car against the side and the top of the frame, means for automatically controlling the level of the platform during its hoisting operation, means for limiting the hoisting movement of the platform with car 70 mounted thereon and means for controlling the maximum height of lift of the empty platform.

4. In a car unloading device, a cylindrical frame, roller means for supporting same, 75 means for rotating the frame on the rollers, a platform passing through the frame and extending on each side thereof, means independent of the frame for supporting and positioning the platform, an electrical hoisting unit secured to the frame and adapted to raise the platform with car mounted thereon and clamp same against the side and top of the frame, means to automatically keep the platform level during the hoisting thereof, 80 means to limit the hoisting movement of the platform and car and to direct the current from the hoisting unit to the rotating means, and means to limit the travel of the platform 85 should same be operated unloaded. 90

5. A device according to claim 4 having an approach and lead off track and V shaped centering device secured to the platform and its supports for aligning rails on the platform with the said tracks. 95

In witness whereof, I have hereunto set my hand.
